Primary Examiner — Philip S Hyder(74) *Attorney, Agent, or Firm* — Alix, Yale & Ristas, LLP(57) **CLAIM**

The ornamental design for a utility knife, as shown and described.

DESCRIPTION

FIG. 1 is a perspective view of a utility knife, portions shown in broken lines showing the new design;

FIG. 2 is a front view thereof;

FIG. 3 is a rear view thereof;

FIG. 4 is a top plan view thereof;

FIG. 5 is a bottom plan view thereof;

FIG. 6 is a left end view thereof; and,

FIG. 7 is a right end view thereof.

No claim is made to the blade portion illustrated in broken lines.
